UNITED STATES PATENT OFFICE.

BENJAMIN M. LEVOY, OF NEW YORK, N. Y.

DESIGN FOR A NOSE-GUARD FOR EYEGLASSES.

No. 39,513.

Specification for Design.

Patented Sept. 8, 1908.

Application filed June 20, 1908. Serial No. 439,628. Term of patent 3½ years.

To all whom it may concern:

Be it known that I, BENJAMIN M. LEVOY, a citizen of the United States, residing at New York city, Manhattan borough, county and State of New York, have invented a certain new, original, and ornamental Design for Nose-Guards for Eyeglasses, of which the following is a specification, reference being had to the accompanying drawing, forming part thereof.

The figure is a face view of a nose-guard for eyeglasses, showing my design.

I claim:

The ornamental design for a nose-guard for eyeglasses, as shown.

BENJAMIN M. LEVOY.
